UNITED STATES PATENT OFFICE.

HORACE S. WALDRON, OF SAVANNAH, GEORGIA.

DEVICE FOR APPLYING PISTON RINGS.

1,420,507.

Specification of Letters Patent. Patented June 20, 1922.

Application filed December 7, 1920. Serial No. 428,999.

To all whom it may concern:

Be it known that I, HORACE S. WALDRON, a citizen of the United States, residing at Savannah, in the county of Chatham and 5 State of Georgia, have invented certain new and useful Improvements in Devices for Applying Piston Rings, of which the following is a specification.

This invention relates to devices for applying piston rings to the pistons of internal combustion or other engines.

As is well known, considerable difficulty is experienced in repair shops, in applying piston rings to the pistons of internal combustion engines before placing the pistons in the cylinders. This difficulty is encountered particularly in applying the rings to the lowermost grooves, the difficulty being in sliding the ring over successive 20 grooves to reach the lowermost grooves.

An important object of the present invention is to overcome the above mentioned difficulties whereby rings may be applied to any of the grooves of the piston with equal 25 facility.

A further object of the invention is to provide such a device which is simple in construction, cheap to manufacture, and which may be easily operated.

30 Other objects and advantages of the invention will be apparent during the course of the following description.

In the drawings, forming a part of this specification and in which like numerals are 35 employed to designate like parts throughout the same,

Figure 1 is a side elevation of the device showing the parts in normal position,

Figure 2 is a section taken on line 2—2 of 40 Figure 1,

Figure 3 is a perspective of the sleeve and associated elements,

Figure 4 is a perspective of the body portion and stationary handle, and,

45 Figure 5 is a view similar to Figure 2 showing the use of a sleeve of a different size.

In the drawings, wherein for the purpose of illustration is shown a preferred embodiment of the invention, the numeral 10 designates the body portion of the device embodying a retaining ring 11 and handle 12 preferably integral therewith. As shown in Figures 2 and 4, the retaining ring 11 is 50 provided at its lower edge with an inwardly projecting annular shoulder 12, for a pur-

pose to be described. The ring 11 is further provided upon its inner face with a pair of diametrically opposite pins 13.

As clearly shown in Figures 2 and 4, I 60 provide a sleeve 14 adapted to be removably carried by the retaining ring 11. The sleeve 14 is provided adjacent its upper edge with a preferably integral collar 15 providing a shoulder 16 adapted to rest upon the 65 annular shoulder 12 of the retaining ring 11. The collar 15 is provided with a pair of diametrically opposite slots 17 adapted to receive the pins 13 of the retaining ring 11. As clearly shown in Figure 3, the slots 70 17 include a vertical portion 18 communicating with a substantially horizontal portion 19. As shown, the sleeve 14 projects a substantial distance below the retaining ring and is tapered adjacent its lower edge 75 as at 20.

Slidably mounted upon the sleeve 14, below the retaining ring 11, is an ejector 21 in the form of a ring adapted to slide upon the sleeve 14. The ejector 21 is provided 80 upon its outer face with a pair of diametrically opposite trunnions 22 for a purpose to be described.

Means for actuating the ejector 21 is provided in the form of an operating member, 85 designated as a whole by the reference numeral 23. The operating member 23 includes a semicircular portion 24, the inner diameter of which is slightly greater than the outer diameter of the ring 21. The 90 ends of the semicircular member 24 are provided with angularly arranged slots 25 adapted to receive the trunnions 22. A pivot pin 26 is provided and adapted to pass through ears 27 and 28 carried by the 95 handle 12 and the operating member 23 respectively. The operating member terminates outwardly in a movable handle 29. The handles 12 and 29 are preferably channeled, as shown in Figure 1, and receive ends 30 100 of a spring, the central portion of which is turned about the pivot pin 26. Thus it will be seen that the spring normally separates the handles whereby the ejector 21 is normally maintained against the 105 lower face of the retaining ring 11.

The numeral 31 designates a piston having ring grooves 32. The inner diameter of the sleeve 14 is preferably slightly greater than the outer diameter of the piston so that the latter may be easily inserted 110 within the sleeve 14, as shown in Figure 1.

The sleeve 14 projects a sufficient distance below the ring 11 and ejector 21 to allow a sufficient number of piston rings 33 to be placed thereon for one piston.

5 In Figure 5, I have illustrated a sleeve 14 having a diameter somewhat less than that shown in Figures 1, 2 and 3, and an ejector 21 having a correspondingly smaller inner diameter. Thus it will be seen that the 10 device may be supplied with a plurality of interchangeable sleeves 14 whereby rings may be applied to pistons of different diameters.

The operation of the device is as follows:

15 A plurality of rings 33 are expanded slightly and placed upon the sleeve 14 as shown in Figure 2. The number of rings applied to the sleeve preferably corresponds to the number of grooves upon each piston. 20 The piston is then inserted within the sleeve 14 and moved upwardly until the lower edge of the sleeve is opposite the upper edge of the lowermost ring groove of the piston. The operator then moves the handle 29 upwardly, the ejector moving downwardly until the lowermost ring on the sleeve 14 is released from the sleeve and snaps into position in the groove. The device is then moved upwardly until the lower edge of 25 the sleeve is opposite the upper edge of the next groove, whereupon the operation is repeated and a ring is placed in the second groove from the bottom. This operation is repeated until each of the grooves has been 30 provided with a ring.

It is to be understood that the form of my invention herewith shown and described is to be taken as a preferred example of the same, and that various changes in the shape, 40 size and arrangement of parts may be resorted to without departing from the spirit of the invention or the scope of the subjoined claims.

Having thus described my invention, I 45 claim:

1. In a device of the character described, a relatively stationary body portion including a depending sleeve, an ejector slidably mounted on said sleeve and provided with 50 a pair of projecting pins, and a handle pivotally connected with said body portion and provided upon its inner end with a yoke, said yoke being provided in its ends with slots adapted to receive said pins.

55 2. In a device of the character described, a relatively stationary body portion, a depending sleeve, means for detachably connecting the upper end of said sleeve to said

body portion, an ejector slidably mounted upon said sleeve, and a handle pivotally connected with said body portion and adapted to actuate said ejector.

3. In a device of the character described, a relatively stationary body portion including a retaining ring, said retaining ring being provided at its lower end with an inwardly extending annular shoulder, a sleeve provided at its upper end with an outwardly extending collar adapted to be received within said body portion, an ejector slidably mounted upon said sleeve, and a handle pivotally connected with said body portion and adapted to actuate said ejector.

4. In a device of the character described, a relatively stationary body portion comprising a retaining ring and stationary handle said retaining ring being provided with inwardly projecting pins, a depending sleeve provided at its upper end with an outwardly projecting collar, said collar being provided with slots adapted to receive said pins, an ejector slidably mounted upon said sleeve and provided with diametrically opposite trunnions, a movable handle, a semicircular member carried by said movable handle, the ends of said semicircular member being provided with slots adapted to receive said trunnions, ears carried by said handles, a pivot pin passing through said ears, and a spring connected between said handles for maintaining said ejector in the normal position.

5. In a device of the character described, a relatively stationary body portion comprising a retaining ring and a stationary handle formed integral therewith, said retaining ring being provided at its lower end with an inwardly extending shoulder, the inner face of said retaining ring being provided with inwardly extending pins, a depending sleeve provided adjacent its upper end with an outwardly projecting collar adapted to rest upon the inwardly extending shoulder of said retaining ring, said collar being provided with slots adapted to receive said pins, the lower end of the outer face of said sleeve being tapered, an ejector slidably mounted upon said sleeve, a movable handle pivoted to said body portion, a semicircular member carried by said movable handle and adapted to actuate said ejector, and means for normally maintaining said ejector in the normal position.

In testimony whereof I affix my signature.

HORACE S. WALDRON.
